N. MCKINLEY,
COPY OR LETTER HOLDER,
APPLICATION FILED DEC. 15, 1916.

1,231,926.

Patented July 3, 1917.

UNITED STATES PATENT OFFICE.

NELLIE MCKINLEY, OF PHOENIXVILLE, PENNSYLVANIA.

COPY OR LETTER HOLDER.

1,281,926.

Specification of Letters Patent.

Patented July 3, 1917.

Application filed December 15, 1916. Serial No. 137,150.

To all whom it may concern:

Be it known that I, NELLIE MCKINLEY, a citizen of the United States, residing at Phoenixville, in the county of Chester, State of Pennsylvania, have invented a new and useful Copy or Letter Holder; and I do hereby declare the following to be a full, clear, and exact description of the invention, such as will enable others skilled in the art to 10 which it appertains to make and use the same.

This invention relates to an improved holder for copy, letters and the like, and one of the objects of the invention is to provide 15 a suitable frame on which the copy, letters or the like may rest, in combination with a suitable clamp on the frame, whereby the copy or the like may be held securely.

Another object of the invention is to provide 20 means on the frame to support the frame slightly above the surface on which the frame rests, whereby a marker or sight guide may be adjusted.

A further object of the invention is to 25 provide guide rods on the side edge portions of the frame on which the marker and sight guide may be adjusted, there being laterally extending ears on the marker for moving the marker, and also supporting a pencil or the 30 like.

In practical fields, the details of construction may necessitate alterations falling within the scope of what is claimed.

The invention comprises further features 35 and combination of parts, as hereinafter set forth, shown in the drawings and claimed.

In the drawings:—

Figure 1 is a view in perspective of the improved copy holder constructed in accordance with the invention.

Fig. 2 is a plan view of the same.

Fig. 3 is a sectional view on line 3—3 of Fig. 2.

Fig. 4 is a longitudinal sectional view on line 4—4 of Fig. 2.

Referring more especially to the drawings, 1 designates a suitable frame, consisting preferably of a sheet metal plate 2, the end edge portions 3 and 4 of which are 50 turned upon themselves to form suitable rolls, to receive the end bars or rods 5 of the wire frame 6. The side edge portions of said sheet metal plate 2 adjacent the end corners

thereof are provided with tongues, which are turned to form rolls or sleeves 7 and 8, to receive the side rods of said wire frame 6. By this construction of rolls 3 and 4, 7 and 8, and the wire frame, the sheet metal plate 2 is thoroughly braced or reinforced.

The side edge portions of the sheet metal 60 plate between the rolls or sleeves 7 and 8 are turned or extended downwardly upon the inner portions of the side rods of said wire frame to form the flanges 9. By means of the flanges, the frame 1 may be supported 65 slightly spaced above the surface on which it rests, the purpose of which will appear later.

A plate or bar 10 extends transversely of the plate 2 and has its opposite ends terminating in rolls or sleeves 11, through 70 which the sides of the wire frame engage, whereby the transverse bar 10 may be guided when adjusted along the sheet metal plate. This bar or plate 10 constitutes a suitable marker, so as to indicate where the copyist 75 leaves off. Furthermore, the bar or plate 10 constitutes a sight guide, whereby the copyist may easily follow the lines in copying. Struck up from the bar or plate 10 is a plurality of lugs or ears 12, which may be 80 grasped, whereby the bar or plate 10 may be adjusted upon the sides 6 of the wire frame. Furthermore, the ears or lugs 12 may constitute supporting means for a pencil or pen or the like. Pivotally mounted at 13 on the 85 sheet metal plate, is a suitable clamp 14, which is under tension of the spring 15, and by applying pressure upon the thumb piece 16, the clamp may be tilted, in order to insert a sheet of copy or the like under the 90 clamp, whereby the transverse bar or plate 10 may be moved over the sheet of copy.

This copyholder may be laid flat on a table or the like, or it may be propped on an inclined position when in use.

The invention having been set forth, what is claimed as new and useful, is:—

A copyholder comprising a plate of rectangular form having its upper and lower margins and the upper and lower portions 10 of the side margins rolled to form hollow beads, a rod secured in the hollow beads and extending about the marginal portion of the plate, the side edge portions of the plate between the upper and lower beads of the 10 side edges of the plate being turned down

to form flanges to so support the plate on a flat support, as to prevent interference with the adjustment of a guide bar on the side rods, and a transverse bar having its ends 5 turned to form sleeves to receive the side rods, whereby the bar may be guided in its adjustments.

In testimony whereof I have signed my name to this specification in the presence of two subscribing witnesses.

NELLIE McKINLEY.
